SOAP GRATER

Charles Iaggi, Salinas, Calif.

Application October 5, 1934, Serial No. 746,965

1 Claim. (Cl. 146—62)

The present invention relates generally to improvements in utility articles and has especial references to dispensing devices devised purposefully for grating and dispensing bar soap in grated form.

5 The principal object of the invention is to provide a soap grater and dispenser that includes positive yet simple means for grating and dispensing the grated soap from a bar of ordinary soap which grated soap is caught in the hands as it drops from the grater.

Another object of the invention is to provide a self-contained grater which holds a bar of soap to be grated and which also provides a 10 sanitary and useful container for the bar of soap when not in use.

A still further object of the invention is to provide a soap grating and dispensing device that is compact, neat in appearance, is durable and 20 that may be economically manufactured.

Still another object of the invention is to provide a soap grater that may be easily installed in any convenient place and that will conserve a bar of soap placed therein.

25 A still further object of the invention is to produce a grater and dispenser that positively and economically reduces a bar of soap to powder form.

Other objects and advantages of the invention 30 will become apparent with reference to the subjoined specification and the accompanying two sheets of drawings in which:

Figure 1 is a side elevation of my improved grater and dispenser shown detachably secured 35 to a wall or the like of a structure;

Figure 2 is an end elevation of the device showing the bar soap container and grating element;

Figure 3 is a bottom plan view of the device looking into the grating mechanism;

40 Figure 4 is a vertical sectional view of the device taken on the line 4—4 of Figure 2 and showing a bar of soap positioned therein, the soap grating elements and the spring for exerting downward pressure on the soap;

45 Figure 5 is an enlarged sectional detail of the grating element as seen looking in the direction indicated by the section line 5—5 in Figure 4; and

Figure 6 is a plan view of the grating element per se.

50 The present application covers an improved form of device over that disclosed in my copending application, filed June 5, 1934, Serial No. 729,076, and it is desired that the present application supplant said former application.

55 Referring particularly to the drawings and especially to Figures 1 and 2 thereof it will be noted that the grater and dispenser includes a rectangular container or casing 8 adapted to be

mounted on suitable supporting brackets 9 and 10 which brackets may be mounted on the wall 11 in any convenient place.

The upper end of this casing is provided with a cap member 12 held in place thereon by means 5 of screws 13, Figures 1, 2 and 4.

Referring to Figure 4, it will be noted that a bar of soap 14 is mounted within the casing and a plunger 15 rests above the soap said plunger being spring pressed against the end of the soap 10 by means of a coil spring 16 mounted in the casing between the plunger and the cap 12.

The lower end of the casing is provided with the grating mechanism 17 and this mechanism includes a sliding element having grooves 18 and 15 19 adapted to receive the tongues 20 and 21 formed on the lower open end of the casing 8.

A groove 22 is formed in the upper face of the grater and a screw 23 arranged on one lip of the casing and extending into said groove limits the 20 lateral movement of the grating element, Figures 2 and 6.

The grating element 17 includes a dispensing nozzle 24 having a dispensing mouth 25 and the grating elements 26 embody a plurality of hock 25 saw blade sections, said blades being diagonally arranged in the grating element, as shown in Figures 3 and 6 and with alternate blades having their teeth in opposed relation.

The soap is ground or granulated by moving 30 the nozzle 24 horizontally back and forth on the tongues 20 and 21 of the casing. This horizontal movement causes the diagonal blades 26 of the grater to pass back and forth in a diagonal granulating or grating action thus grating the lower 35 end of the soap bar and allowing the grated or granulated soap to drop into the hand of the operator, the while the operator holds the palm of the hand over the nozzle opening 25.

Due to the diagonal or oblique arrangement 40 of the grating blades 26 the soap is more easily and properly ground with less effort on the part of the operator than if the blades were arranged crosswise as this diagonal or oblique arrangement gives the blades a better cutting action on the 45 soap.

I claim and desire to secure by Letters Patent of the United States the following:

In a grating and dispensing device of the class described including a casing, a dispensing 50 nozzle slidable across the lower end of said casing, a grating device carried by the upper portion of the nozzle, said grating device embodying a plurality of diagonally disposed saw blades, said blades having their teeth arranged in opposition 55 to each other as to alternate blades.

CHARLES IAGGI.
